ADJUSTABLE LOCKING DEVICE

Louis L. Deal, Rye, N. Y., assignor to Deal Slide-Lock Devices, Inc., New York, N. Y., a corporation of New York

Application February 19, 1947, Serial No. 729,572

17 Claims. (Cl. 16—193)

1

The present invention relates to adjustable locking devices and more particularly to the type disclosed in Patent No. 2,380,030 granted to Erastus C. Deal. The present invention constitutes an advance over and further extends the usefulness of such adjustable locking devices.

It has been found desirable in some instances to adjustably support or retain a member or part in position in such manner that it may be moved in one direction upon the application of a relatively small amount of force and which resists movement in an opposite direction until the applied force reaches a comparatively greater value. One example of such use is in connection with windows; the window should be readily liftable and yet the lock or retaining means should effectively support the weight of the window until such time as sufficient additional force is applied to the window in a direction tending to close it. This feature is particularly desirable in instances where it is desired to support vehicle windows of busses, railroad coaches, street cars and the like; such windows are subject to a considerable amount of vibration when passing over rough spots in a road or track and vibration incident to these shocks may be sufficient to gradually jar a window from open to closed position. It is desirable to avoid this accidental closing and to securely hold the window until such time as it may be desired to close it; applicant's present adjustable locking device effectively performs this objective. Another example of use for the present adjustable locking device is in those instances where it is desirable to readily move a machine part to take up slack or lost motion and yet to prevent movement of the machine part upon the application of excessive force which might otherwise subject the machine part to breakage.

The present invention aims to provide an improvement over Patent No. 2,380,030 and to accomplish the above referred to and other desirable objectives by providing an adjustable locking device that is adapted to be moved in one direction by the application of a relatively small force and which requires a comparatively larger force to move it in an opposite direction.

An object of the present invention is to provide a new and improved locking device.

Another object of the invention is to provide an improved locking device adapted to be moved in one direction by a relatively small force and in an opposite direction by a relatively larger force.

Another object of the invention is to provide an adjustable locking device particularly adaptable to support a window.

2

A further object of the invention is to provide a mechanism which may be incorporated with existing adjustable slide locks with minimum revision thereof.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a fragmentary perspective view showing a preferred embodiment of the present invention;

Fig. 2 is an end view of the embodiment illustrated in Fig. 1;

Fig. 3 is a fragmentary sectional view, partially broken away, illustrating the present adjustable locking device in assembled relationship;

Fig. 4 is a sectional view of a modified form of the invention;

Fig. 5 is an enlarged fragmentary view showing a bracket modification;

Fig. 6 is a sectional view, partially broken away, showing another form of the invention; and

Fig. 7 is an exploded perspective view showing the parts of the adjustable locking device illustrated in Fig. 6.

The present invention will be described chiefly with reference to its use in a vertically movable window as it is believed that such will more clearly bring out the features of the invention. It will be clear that the invention is equally applicable to various other structures.

Referring more particularly to Figs. 1, 2 and 3 of the drawing there is shown a portion of a window frame 1 adapted to carry a sheet of window glass or other transparent material, the frame 1 being secured to a bracket-like member or means 2 by screws, bolts or other suitable means 4. As shown, the bracket or means 2 which is adapted to carry a load is provided with laterally extending portions or tabs 5 that in use project into a guideway or channel member 7 and the bracket has a flange 8 at one side extending

along the side of the channel member or guideway 7 to assist in guidance of the bracket during movement of it and the window frame with respect to the guideway. The guideway 7 may be secured to the sides of a window opening by any suitable means, such as screws or bolts, that may

extend through apertures 10 in the guideway; the guideways or channels 7 may also be secured in position by spot welding or the like. Preferably the guideway is provided with flanged edges 11 that project inwardly toward each other from opposite sides of the guideway to form retaining means for maintaining the bracket or load-carrying means 2 in assembled relationship with the guideway 1. The bracket 2 is also shown provided with apertures or slots 13 and 14, through which may extend pins or projections 15 and 16 carried by the internal mechanism of the present slide lock.

For purposes of convenience the present adjustable slide lock will be described chiefly with reference to a single bracket and channel, but it is to be understood that in normal use for supporting a window each side of the window opening will be provided with similar mechanisms. The description of the construction and mechanism at one side of the window will suffice for that at the other side of the window.

The internal mechanism of the present slide lock is adapted to facilitate movement of the window frame or the like 1, through the bracket 2, with respect to the guideway 1 and yet to retain the window frame in any desired position to which it may be opened or adjusted. With a vertically movable window frame the window is subject to the force of gravity and the locking or holding means should securely support the weight of the window and yet be readily movable with the window to closed or to open positions. The mechanism illustrated more particularly in Fig. 3 is adapted to efficiently perform this task. The locking means illustrated in this latter figure comprises a plurality of wedge-like members 17 and 18 (here shown as two) having complementary inclined faces 17a and 18a, between which passes a flexible ribbon or cable member 20. The latter flexible member 20 may be fastened to the guideway 1 adjacent the ends thereof by spot welds 22 or in any other suitable manner.

Urging together of the wedges causes the complementary surfaces 17a and 18a to tend to press the wedges outwardly so that the outer sides or edges thereof 17b and 18b engage firmly with the side walls of the channel or guideway 1. The flexible member 20 facilitates the spreading action of the wedges and tends to generally improve the operation of the mechanism; while a flat ribbon-like member 20 is illustrated in the drawing it will be clear that this member could have round, oval or other suitable shape to co-operate with appropriately shaped faces on the wedges 17 and 18.

The wedges 17 and 18 are normally urged together or toward each other by a resilient member or spring 23 shown abutting against a lower tab portion 6 of the bracket 2 and disposed within a lower wedge recess or slot 25 so that it presses the wedge member 17 toward the adjacent upper wedge member 18. The slot-like recess 25 assists in retaining the spring 23 in operating position. While a spiral or helical spring is shown urging the wedge member 17 toward the wedge member 18, any other form, shape or type of resilient means may be utilized for this purpose.

For purposes of convenience in description the wedge 17 will be hereinafter referred to as the "lower" wedge, the wedge 18 as the "upper" wedge and the spring 23 as the "locking" spring.

The locking spring 23 is preferably of relatively weak or light capacity; it is of such nature that it exerts a relatively small effective force on the

lower wedge 17. Urging of the lower wedge 17 toward the upper wedge 18 by the locking spring 23 tends to spread the wedges laterally with respect to each other so that they may firmly engage with the walls of the channel member or guideway 1.

Intermediate the upper wedge 18 and the upper tab 5 of the bracket member 2 is shown a spring 26 in a recess 24, which will be hereinafter referred to as the "load" spring. The load spring 26 is of greater capacity than the locking spring 23 and is adapted to exert greater effective force than the force exerted by the locking spring 23. The load spring 26 may be a stronger or heavier spring than the locking spring 23 or it may be more highly stressed or compressed, as described below, so that it exerts a greater effective force than does the locking spring. As shown in Fig. 3 the load spring 26 is formed of slightly larger diameter wire than the locking spring and is compressed to a greater extent due to the intermediation between it and the upper bracket tab 5 of a slug or spacer element 28, connected with the bracket member 2 by a protuberance or pin 29 in such manner that the spacer element moves to and fro or up and down with the bracket member 2. For minimizing objectionable rattling or noise a felt pad, rubber pad or cushion 31 is preferably inserted intermediate the upper bracket tab 5 and the top of the spacer element 28.

In operation, assuming the window to be in partially open position, the window frame 1 is supported by the bracket 2 on the internal locking wedges 17 and 18 through the intermediation of the relatively large capacity load spring 26. If the window is a vehicle window shocks and jars caused by road shocks are absorbed by the load spring 26; the frame 1, bracket 2 and spacer element 28 vibrate up and down on the load spring 26. The load spring 26 thus supports the window in operative position, being selected of such appropriate capacity or size as to satisfactorily perform this task. If it is desired to close the window an individual may press downwardly upon the window sufficiently far as to move the upper edge 13a of the bracket slot 13 against the operating pin 15 of the lower wedge 17. This, in effect, compresses the load spring 26 and continued downward pressure tends to pull the lower wedge member 17 away from the upper wedge member 18; the wedges are thus unlocked from their engagement with the guideway walls. The upper bracket tab 5, intermediate load spring 26 and spacer 28 causes the upper wedge 18 to move along after the lower wedge member 17 during downward movement of the window. When the window has been moved downwardly sufficiently far the individual may remove his hands from it and the window automatically locks into the position at which it is released; this is due to the immediate locking effect of the co-operating wedges 17 and 18 and walls of the guideway or channel member 1.

The load spring 26 may be of such caliber, capacity or effective characteristics as to support the weight of the window in such manner as to normally maintain the edge 13a of the bracket slot 13 out of contact with the operating pin 15 of the lower wedge 17, yet it is of such characteristics as to be compressed upon the application of sufficient additional force to permit closing of the window in the manner described immediately hereinabove. The particular load spring utilized should be such as to effectively support the window or other part and yet to facilitate movement

of the window or part upon the application of manual pressure. Different capacity load springs will generally be utilized with different weights of windows.

When it is desired to open the window an individual lifting the window moves the frame 1 and bracket 2 upwardly so that the lower edge 14a of the bracket recess 14 comes into contact with the operating pin 16 carried by the upper wedge 18 and serves to "release" the lock from its sidewall engagement. Since the locking spring 23 is of relatively weak capacity compared to the load spring 26 the force required to move the window and bracket upwardly is relatively small. As the window and bracket move the upper wedge 18 upwardly the lower bracket tab 6 and locking spring 23 cause the lower edge 17 to follow along behind the upper wedge.

In some instances it may be desired to omit the spacer element 28 and to utilize a spring which extends from the upper wedge 18 into abutting relationship with the upper bracket tab 5. The spacer element 28 permits the use of a shorter length of spring and initially compresses it so that it exerts a greater resilient effect than does the locking spring 23.

Fig. 4 illustrates a modified form of the invention. In this figure the upper wedge 27 and lower wedge 30 are each shown provided with apertures 32 and 33, respectively, into which extend projecting portions or pins 16a and 15a carried by the bracket 2a. The projections or pins 16a and 15a act as operating pins in a manner similar to the pins 15 and 16 described in connection with Figs. 1 through 3. Upon upward movement of the bracket 2a with a window the upper side of the operating projection 16a moves into contact with and pulls the upper wedge 27 to thus release the lock. Upon downward movement of a window and bracket the lower part of the operating projection 15a moves into contact with the bottom edge of the aperture 33 of the lower wedge 30 to release the lock.

The tab portion 9 carried at the upper part of the bracket 2a, and which is effective to hold the spacer element 21 down in opposition to the load spring 26a, comprises a flat piece which may extend into the guideway 7a substantially at right angles to the supporting part of the bracket 2a.

The construction and operation of the modified form disclosed in Fig. 4 are generally like that brought out in connection with Figs. 1 through 3 but in some instances it may be desirable to provide the operating projections or pins on the bracket member instead of on the wedges; Fig. 4 shows a satisfactory construction embodying these features. While the operating pins 15a and 16a of this figure are shown punched out of the bracket 2a, they may, of course, be provided by attaching suitable pins to the bracket without punching them out of the bracket material.

Fig. 5 shows an enlarged fragmentary view of a bracket tab 12 which extends around to the inner side of a flange 11b of the guideway 1b. This construction facilitates retention of the bracket 2b with the guideway 1b. The tab or guideway portion at the opposite end of the bracket 2b may be similar to that of Figs. 1 through 4 and may be retained within the guideway 1b in similar manner.

In Figs. 6 and 7 there is illustrated another form of the present invention. In this form of the invention a guideway or channel member 35

is adapted to contain a lower wedge member 36, similar to that described in connection with Figs. 1 to 3, and also to contain an upper wedge member 37, the upper wedge member 37 being generally similar to the wedge member 18 but provided with a flattened end or straight upper surface in lieu of a recess. A flexible ribbon-like member 38 of steel or other suitable material is shown extending between the complementary surfaces of the upper and lower wedges 36 and 38. A saddle or cover member 40 having apertures 41 and 42 and tabs 44 and 45 at opposite ends thereof is adapted to be retained in position by oppositely disposed and inwardly extending flanges of the guideway 35. Operating pins 46 and 47 of the wedge members 36 and 37 project through the apertures 41 and 42 of the cover or saddle member 40.

The lower saddle tab 44 forms an abutment for a relatively weak or small capacity locking spring 48 that fits into a recess in the lower wedge 36. A load spring 49 rests against the flat end of the upper inwardly extending saddle tab 45, the latter resting against the upper end of the locking wedge 37.

The load spring 49 is shown of slightly heavier wire and general construction than the locking spring 48 and as maintained in partially compressed relationship by a spacer member 50 which rests against the upper end of the load spring 49 and is held in operative position by an inwardly extending ear 52 of the bracket member 34. The bracket member 34 may be secured to a window frame (not shown) by screws or bolts 53 and has an aperture or recess 54 adapted to fit around or receive the operating pin or protuberance 47 carried by the upper wedge member 37.

When a window is lifted, the lower edge 54a of the bracket recess 54 presses against the operating pin 47 of the upper wedge 37 and tends to "pull" the upper wedge slightly away from the lower wedge 36; this releases the locking action and permits upward movement of the window. When the window is released the mechanism automatically retains the window in adjusted position. When it is desired to close the window the individual presses downwardly on the window and tends to compress the load spring 49 sufficiently far to move the lower end 55 of the bracket member 34 into contact with the operating pin 46 of the lower wedge member 36; this tends to pull the lower wedge member 36 away from the upper wedge member 37 and to allow movement of the lock and window to a desired position. The force normally exerted by the load spring 49 is of such value or effect as to normally support the window in fixed position since it carries the weight of the window and absorbs vibration of the window due to road shocks or the like. The application of sufficient additional force to the window in a direction tending to close it is sufficient to compress the load spring 49 and move the releasing edge 55 of the bracket against the operating pin 46.

Use of such terminology as "load-supporting" or "load-carrying" in the description and claims in referring to means or elements is for purposes of clarity. It is not intended to thereby infer that a part or member must carry or support a load at all times, as that may or may not be the situation.

It will be seen that the present invention provides a new and improved adjustable locking device or slide lock which is adapted to maintain an article or part, such as a window, in adjusted position at all times during normal conditions

and yet which is adapted to facilitate closing of the window upon the application of a slight amount of force in addition to that caused by the weight of the window. The small capacity locking spring facilitates ready movement of the mechanism and window to open or further opened positions. Easy lifting of a window is possible and yet danger of the sash accidentally dropping is minimized; the construction minimizes the possibility of vibration due to road shocks or the like causing accidental dropping of the window. The device is simple in construction and operation, possesses relatively few parts, and is well adapted to withstand rough usage to which it may be subjected.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a device of the class described, in combination, a guideway, a plurality of wedge-like locking members in said guideway, resilient means adapted to normally urge said wedge-like members into locking engagement with the guideway, a load-carrying member, projecting means operatively interconnecting said wedge-like members and said load carrying member facilitating adjustment of the device along the guideway and second resilient means operatively interposed between the load carrying member and said projecting means adapted to support said load-carrying member and adapted to exert a greater effective force than said first-mentioned resilient means but adapted to yield to facilitate selective positioning of said device upon the application of sufficient force to said load-carrying member.

2. A device of the class described, comprising, in combination, a guideway, a plurality of locking members in said guideway, load-carrying means, portions connecting with the load-carrying means projecting into said guideway adjacent opposite ends of said locking members, resilient means intermediate one of said projecting portions and a locking member adapted to urge the locking members into engagement with the guideway, and second resilient means adapted to provide greater effective force than said first resilient means normally maintaining said load-carrying means in a set position but adapted to yield for shifting of the device upon application to the load-carrying means of a force greater than that normally exerted by said second resilient means, and means operatively connecting said locking members and said load-carrying means providing for movement of the device along the guideway.

3. A device of the class described comprising, in combination, a guideway, a plurality of locking members in said guideway, load-carrying means, portions connecting with the load-carrying means projecting into said guideway adjacent opposite ends of said locking members, resilient means intermediate one of said projecting portions and a locking member adapted to urge the locking members into engagement with the guideway, and second resilient means adapted to exert greater effective force than said first resilient means intermediate another of said projecting portions and a second locking member normally maintaining said load-carrying means in a set position but yieldable for shifting of the device

upon application to the load-carrying means of a force greater than that normally exerted by said second resilient means, and projecting portions operatively interconnecting said locking members and said load-carrying means and facilitating lengthwise movement of the device lengthwise of the guideway.

4. A device of the class described comprising, in combination, a guideway, a plurality of locking members in said guideway, load-carrying means, portions connecting with the load-carrying means projecting into said guideway adjacent opposite ends of said locking members, a small capacity spring intermediate one of said projecting portions and a locking member adapted to urge the locking members into engagement with the guideway, and a second spring of greater effective force than said first spring normally maintaining said load-carrying means in a set position but adapted to yield for shifting of the device upon application to the load-carrying means of a force greater than that normally exerted by said second spring, and means operatively connecting said locking members and said load-carrying means to facilitate movement of the device along the guideway.

5. In a device of the class described, the combination of a guideway, a plurality of wedge-like members in said guideway, load-supporting means having portions extending into the guideway adjacent opposite ends of said wedge-like members, relatively small effective capacity resilient means intermediate one of said extending portions and a portion of a wedge-like member adapted to urge the wedge-like members into engagement with the guideway, relatively larger effective force resilient means intermediate another of said extending portions and a portion of a wedge-like member adapted to normally maintain said load-supporting means and a load in set position, and projections operatively connecting said wedge-like members and said load-supporting means adapted to facilitate selective positioning of the device upon application of forces sufficient to overcome the effective forces of said resilient means.

6. In a device of the class described the combination of a guideway, a plurality of wedge-like members in said guideway, load-supporting means having portions extending into the guideway adjacent opposite ends of said wedge-like members, a spring of relatively low effective capacity intermediate one of said extending portions and a wedge-like member adapted to urge the wedge-like members into engagement with the guideway, a spring of comparatively large effective capacity intermediate another of said extending portions and a wedge-like member adapted to normally maintain said load-supporting means and a load in set position, and projections operatively connecting said wedge-like members and said load-supporting means adapted to facilitate selective positioning of the device upon application of forces sufficient to overcome the effective forces of said springs.

7. In a device of the class described, the combination of a guideway, a plurality of wedge-like members in said guideway, a load-supporting bracket having portions extending into the guideway adjacent opposite ends of said wedge-like members, a relatively weak spring intermediate one of said extending portions and a wedge-like member adapted to urge the wedge-like members into engagement with the guideway, a spacer member in said guideway and resting against

another of said extending portions, a spring intermediate said spacer member and a wedge-like member adapted to normally maintain said load-supporting bracket and a load in set position, and projections operatively connecting said wedge-like members and said load-supporting bracket adapted to facilitate selective positioning of the device upon application of forces sufficient to overcome the effective forces of said springs.

8. In a device of the class described, the combination of a channel member, a plurality of co-operating locking wedges in said channel member, a flexible ribbon-like member extending between complementary surfaces of said wedges, projections carried by said wedges and extending out of the channel member, a bracket-like member having apertures through which said projections extend, spaced portions carried by said bracket-like member extending into the channel member adjacent opposite ends of the locking wedges, resilient means of comparatively small effective force maintained in position by one of said portions and normally urging said wedge members into engagement with the channel member, and resilient means of comparatively large effective force maintained in position by another of said portions and resting against one of said wedges so that said bracket-like member may be moved in one direction by the application of a small force and movement in an opposite direction requires a comparatively larger force.

9. In a device of the class described, the combination of a channel member, a plurality of co-operating locking wedges in said channel member, a flexible ribbon-like member extending between complementary surfaces of said wedges, projections carried by said wedges and extending out of the channel member, a plate member having apertures through which said projections extend facilitating shifting of the wedges upon movement of the plate member to a different position, spaced tabs carried by said plate member extending into the channel member adjacent opposite ends of the locking wedges, resilient means in said channel adapted to exert a comparatively small effective force abutting against one of said tabs and normally urging said wedge members into engagement with the channel member, and resilient means in said channel adapted to exert a comparatively larger effective force maintained in position by another of said tabs and resting against one of said wedges so that said plate member may be moved in one direction by the application of a small force and movement in an opposite direction requires a comparatively larger force.

10. In a device of the class described, the combination of a guideway, locking wedges in said guideway having projections extending beyond the guideway, a cover extending over said wedges having apertures through which said projections extend, tabs carried by said cover and extending into the guideway adjacent the ends of the wedges, resilient means intermediate one of said tabs and one of said wedges exerting a relatively small effective force, bracket means operatively associated with said wedges having a lug projecting into the guideway, and resilient means intermediate said lug and a second tab carried by the cover exerting a relatively larger effective force than said first-mentioned resilient means.

11. In a device of the class described, the combination of a guideway, locking wedges in said guideway having projections extending beyond

the guideway, a cover extending over said wedges having apertures through which said projections extend, tabs carried by said cover and extending into the guideway adjacent the ends of the wedges, resilient means intermediate one of said tabs and one of said wedges exerting a relatively small effective force, bracket means operatively associated with said wedges and overlying said cover having a lug projecting into the guideway, a spacer member in said guideway, and resilient means intermediate said spaced member and a second tab carried by the cover exerting a comparatively larger effective force than said first-mentioned resilient means.

15. In a device of the class described, in combination, a guiding member, a plurality of holding members guided by said guiding member, resilient means normally maintaining said holding members in engagement with the guiding member,

20. a load-carrying member, and yieldable load-supporting means capable of normally exerting a comparatively larger effective force than said resilient means operatively interposed between said holding members and said load-carrying member adapted to normally support a load in selected position and yieldable in response to application of a force in addition to a load effective upon said load-carrying member to facilitate adjustment of the device to a different position.

30. 13. In a device of the class described, the combination of a guideway, wedge-like members in said guideway, attachment means for supporting an object, laterally projecting means operatively interconnecting said wedge-like members and

35. said attachment means to facilitate movement of the device along the guideway, resilient biasing means operatively interposed between said attachment means and said wedge-like members adapted to yieldably carry said attachment means

40. on said wedge-like members with a portion of the attachment means spaced from said projecting means, said biasing means tending to urge the attachment means in one direction along the guideway and being yieldable upon movement of

45. the attachment means in an opposite direction to provide contact between a projecting means and said portion of the attachment means for moving a wedge-like member and unlocking the wedge-like members from engagement with the guideway,

50. movement of said attachment means in said one direction providing contact between a projecting means and another portion of the attachment means for unlocking the wedge-like members and moving the device in said one direction.

55. 14. In a device of the class described, the combination of a guideway, wedge-like members in said guideway, attachment means adapted to support an object on said wedge-like members,

60. means extending generally transversely of said guideway and interconnecting said wedge-like members and said attachment means for facilitating release of engagement between the wedge-like members and the guideway and movement

65. of the device to different positions along the guideway, and resilient biasing means in said guideway urging said wedge-like members and a portion of said attachment means apart and tending to urge said attachment means in one direction along the guideway, movement of the attachment means in said one direction providing a contact between said transversely extending

70. means and said attachment means for releasing said engagement and moving the device along the guideway, movement of the attachment means in

opposition to the effect of said resilient biasing means providing a contact between said transversely extending means and said attachment means for releasing said engagement and moving the device in an opposite direction along the guideway.

15. In a device of the class described, the combination of a guideway having spaced walls, holding means movable along said walls and adapted to engage with each of said spaced walls, means facilitating engagement of the holding means with each of said spaced walls, attachment means normally retained in position by said holding means, means operatively interconnecting the holding means and the attachment means for adjusting the device along the guideway, yieldable means operatively interposed between said holding means and said attachment means for yieldably supporting a window in an open position and normally tending to urge the attachment means upwardly along the guideway but adapted to yield upon the application to such window of sufficient window-closing force to provide a contact between said interconnecting means and said attachment means for releasing engagement of the holding members with said spaced walls for closing of such window, movement of the attachment means upwardly providing a contact between said interconnecting means and said attachment means for releasing said engagement of the holding members with said spaced walls for opening of such window.

16. In a device of the class described, the combination of a guideway including oppositely spaced walls, holding members in said guideway and movable along said walls adapted to lock into engagement with said oppositely spaced walls, means carried by said holding members and normally retained in position by said holding members adapted to support a window, said holding members and said means having co-acting projections and recesses for facilitating movement of the device, and yieldable biasing means operatively interposed between said means and said holding members, said biasing means adapt-

ed to normally yieldably support such a window in an open position and normally tending to urge said first means upwardly along the guideway but adapted to yield under the influence of sufficient force to provide a contact between a said projection and an edge of a co-acting recess for unlocking said holding members and closing of such a window, movement of said first means upwardly providing a contact between another of said projections and an edge of a co-acting recess for unlocking said holding members and opening of such a window.

17. In a device of the class described, the combination of, a guideway having oppositely spaced walls, a plurality of overlapping wedge-like holding members in said guideway movable along and engageable with said oppositely spaced walls and provided with means projecting out of said guideway adapted to be operatively connected with an object to be held, yieldable means for operative interposition between said wedge-like members and the object to be held adapted to yieldably support said object and adapted to normally urge the wedge-like members into engagement with the guideway, movement of said object in one direction compressing said yieldable means and providing a contact between a portion of said object and a projecting means of one wedge-like member for releasing engagement of the wedge-like members with the guideway, and movement of said object in an opposite direction providing a contact between another portion of the object and a projecting means of another wedge-like member for releasing engagement of the wedge-like members with the guideway.
